TONE ARM MOUNTING

Robert M. Cain, Charlotte, Mich., assignor to Wilcox-Gay Corporation, Charlotte, Mich., a corporation of Michigan

Application May 23, 1945, Serial No. 595,293

3 Claims. (Cl. 274—23)

1

This invention relates to mechanisms for carrying the pick-up or playback arm of a phonograph.

In order for the pick-up arm to follow the groove of a conventional disc record, it is necessary that the arm swing first about a vertical axis so that it may follow the spiralling of the grooves; and, second, it is necessary that it also rotate about a horizontal axis so that the needle may follow up and down variations in the record, and so that the pick-up arm may be raised for removal or insertion of the record.

In many phonograph designs incorporating pivots or shafts as the horizontal axis, there is usually a certain amount of friction opposing the rotation. This friction adds itself to the weight of the pick-up arm on the "up" direction and subtracts itself from the weight of the pick-up arm on the "down" direction. It can be seen then that the actual change in needle pressure, due to this axial friction, is substantially twice the increment of friction.

While this change in needle pressure might represent a relatively small percentage of the total in phonographs having needle pressures of several ounces or more, it represents a substantial percentage of the total in pick-ups of the "light weight" class.

In the playing of most phonograph records there is present a certain amount of "scratch noise." The amount of this scratch is dependent on several factors such as the initial quality of the record, the extent to which it has previously been played, the response of the pick-up device and associated amplifying circuits, the reproducing stylus and, to a large extent, the associated weight.

When playing phonograph records of the conventional disc type on record playing machines of existing design, the up and down variations of record surface result in a varying scratch level due to the variation in needle weight. The variation in scratch level actually makes the noise more noticeable and therefore more objectionable than it would if it were substantially steady.

One means of maintaining constant needle pressure in a phonograph pick-up arm and consequently constant scratch level would be to play only the flattest of record surfaces on an exactly "true" turntable thereby maintaining constant needle elevation. This would be commercially unfeasible.

It is therefore an object of this invention to provide a phonograph pick-up arm and a suitable mounting which will result in the ability of

2

the reproducing needle to follow up and down variations in the record and yet maintain sufficiently constant needle pressure so that a high order of "noise" constancy is obtained.

5 In phonographs using pick-up arms and conventional pick-up devices it is desirable that proper needle pressure be employed. This pressure should be sufficient to cause the needle tip to bear against both walls of the groove at all times. Greater pressure than an amount necessary to accomplish this results in excessive wear on both the needle and the record. Insufficient pressure allows the needle to climb the walls of the groove and results in a distortion of the recorded production.

In phonographs having a certain amount of friction opposing the vertical rotation of the pick-up arm, it is necessary that the static needle pressure be enough greater than the amount necessary for proper tracking so that when the arm is following a downward variation of the record surface, the loss in weight due to the axial friction will still leave sufficient for proper tracking. As has already been shown, the needle weight becomes still greater when the arm is following an upward variation in the record and the axial friction adds itself to the already over-weighted arm.

10 It is another object, therefore, of this invention to provide a phonograph arm and a suitable mounting in which the horizontal axial friction opposing the vertical rotation of the arm is negligible.

It is a further object of this invention to combine with the mechanism which facilitates vertical movement of the pick-up arm means for adjusting the needle pressure.

15 It is a further object of this invention to proportion the dimensions and divisions of stops in such a manner that two objectional accidents cannot occur, namely, that it will be impossible for the needle holder to drag on the record in the absence of a needle and that it will be impossible for the needle to drag on the turntable in the absence of a record.

20 It is another object of this invention to so arrange the stops and needle pressure control means (such as a tension spring) that the adjustment of the tension spring remains substantially constant and the needle pressure control means is not unduly relaxed when the pick-up arm is raised.

The foregoing and many other objects of my invention will become apparent in the following description and drawings in which

Figure 1 is a schematic diagram of the essential mechanism for accomplishing the purposes of this invention.

Figure 2 is a plan view of a practical embodiment of the invention.

Figure 3 is an elevation in partial section of the mechanism of Figure 1 taken on line 3—3 of Figure 2.

Figure 4 is a rear view in section of Figure 3.

Figure 5 is a top sectional view through the 10 plane indicated in Figure 3 by the numbers 5—5.

Figure 6 is a reproduction of part of Figure 3 with the playback arm in a partly elevated position.

Figure 7 is a reproduction of Figure 6 with the playback arm elevated to a vertical position.

Referring to Figure 1, the pick-up arm supporting assembly *a* carries the play-back arm *1* and is mounted on supporting assembly *b*. The playback arm *1*, needle *12* and its rearwardly directed extension carrying pin *6* are all supported on a knife edge bearing *10* resting, in turn, on assembly *b* consisting of a fulcrum *11* carried on a support *2* which is pivoted on pin *5*.

As was mentioned previously, it is necessary for a pick-up arm to rotate first of all in a horizontal plane around a vertical axis. By means of a vertical spindle secured to the support of pin *5*, a frame of reference rotatable about a vertical axis is established. The plane of the drawing of Figure 1 is presumed to be attached to this frame of reference rotating around the vertical axis. More specifically, assembly *b* is pinned to this frame of reference by means of pin *5* which forms a horizontal axis around which assembly *b* may rotate. Stop *3* is also attached to this frame of reference.

In Figure 1, *W* represents the weight at the center of gravity of the pick-up arm. The weights of other members are functionally negligible. In Figure 1, the mechanism is shown in an intermediary position in which there could not be an equilibrium under the action of the weight *W* alone. In this position, assembly *a* is still free to rotate about fulcrum *11*, and assembly *b* is still free to rotate about pin *5*. Under the action of weight *W*, assembly *b* would rotate around pin *5* until member *2* struck stop *3*, after which assembly *b* would become relatively rigid with the frame of reference. Thereafter, assembly *a* would rotate around fulcrum *11* until member *9* struck stop *7*. In this position, the force exerted by stop *7* and stop *3* would bring the mechanism to equilibrium, in the absence of any needle forces exerted at *12* or in the absence of a tension spring such as spring *4*.

In this invention, the positioning of the stops and other dimensions may be so arranged that this condition would obtain if no needle were in the pick-up arm or if no record were on the turntable. This would make it impossible for the needle holder to drag on the record or for the needle to drag on the turntable. If, however, a record were on the turntable and a needle were in the holder, the needle would strike the record before this position is attained.

As the playback arm is lifted by a force applied at *12* to move the mechanism out of the previously described position of equilibrium, it can be seen that not only is it possible for assembly *a* to begin to rotate around fulcrum *11*, but that it is also possible for the relatively rigid combination of assemblies *a* and *b* to begin to rotate around pin *5*. If the second of these positions obtains, it is

seen that the force on the needle required to raise assembly *a* would be nearly equal to the weight of the entire pick-up. If, however, the first of these conditions obtains, then it is seen that the force required at the needle would be determined by the tension of spring *4* as well as by the weight of the pick-up arm—and it is seen that the greater the tension of spring *4*, the less force is required at *12*.

Since the desirable needle pressure is always considerably less than the weight of the pick-up arm, it is one of the purposes of this invention to adjust the tension of spring *4* so that a relatively small force exerted at *12* will lift the mechanism out of the equilibrium positive by the first mentioned possibility—namely, that assembly *a* rotates first about fulcrum *11*, while assembly *b* remains relatively rigid to the frame of reference by resting on stop *3*.

In this invention the dimensions would be so proportioned that in the playing position with a record on the turntable and a needle in the holder, member *9* would lie between stops *7* and *8* touching neither even for any possible vertical movement of one due to irregularities in the record or turntable.

In a practical embodiment of the invention, as will be shown later, the tension of spring *4* is adjustable so that various desired needle pressures may be obtained.

Also, it will be seen that the tension on spring *4* will be varied in operation only by the degree of movement of the playback arm between stops *7* and *8*; and after member *9* has struck stop *8*, tension of spring *4* will cease to relax. Accordingly, spring *4* may, if desired, simply be hooked over pins *6* and *5* and will not be accidentally released.

If now it is desired to change a record or to move the pick-up arm out of the way for any other purpose, such as would be necessary if the pick-up arm were used as a playback arm on a record cutting machine (having other elements which must cooperate with the turntable to cut a record), one lifts member *1* by the application of additional manual forces at *12*. When this is done, assembly *a* rotates around fulcrum *11* until member *9* strikes stop *8*, after which members *a* and *b* become relatively rigid and rotate around pin *5*. The extent of this rotation is limited only by other obstructions.

In a practical embodiment of the invention, elements would be so arranged that rotation around pin *5* is possible until the center of gravity represented in Figure 1 by *W* has at least passed to the right of pin *5*, after which the pick-up arm would strike some obstruction. The weight *W* would then hold the arm in the elevated position.

From Figure 1, it is seen that it is possible to remove knife edge *10* from V-groove *11* entirely by the application of proper forces. In a practical embodiment of the invention, as will be shown later, stops may be arranged so that this cannot happen inadvertently.

Referring now to Figures 2 and 3, the phonograph base plate *19* carries the rotatable turntable *18* in any suitable manner and the vertical journal *13* of the pick-up arm assembly which journal is bolted to the base *19* by means of nut *17* and washer *16*. Through this journal *13* runs a spindle *15* to which is rigidly attached member *R*. The upper part of journal *13* is reduced in diameter at *14* and the top face of this reduced portion of journal *13* cooperates with the under-

side of member R in such a way that the spindle 15, member 4 and journal 13 form a combination low friction rotational and thrust bearing which carries the load of the pick-up arm and allows rotation in a horizontal plane of member R and consequently of the pick-up arm.

In this practical embodiment of the invention, member R is the frame of reference to which the schematic diagram of Figure 1 was referred. Member R comprises a single piece of sheet metal bent along three lines to form a horizontal and three vertical parts. The horizontal part which attaches to spindle 15 carries the vertical parts which form a fork-shaped yoke. The pin 5 is carried in any suitable manner between the sides of the yoke. Pin 5 carries member B. Member B consists of a piece of sheet metal bent into a channel, the lower extremity of the sides of this channel being drilled to cooperate with pin 5. Member B therefore is rotatable about pin 5. The upper extremities of the sides of member B have V-slots 11 on which bear a knife edge 10 which is part of member 9. Member 9 consists of a piece of sheet metal with a single bend forming an inverted L.

The vertical side of member 9 is cut away, as shown most clearly in Figure 4, to form the knife edges 10 and to extend downward to extremity 9a, whose operational function was described in Figure 1. Member 9 is spot welded or otherwise permanently attached to main pick-up arm 1, which has the form of a channel member closed on both ends.

Pick-up arm 1 carries at one extremity needle 12 and an electrical pick-up mechanism not shown. The other extremity of member 1 is drilled to pass machine screw 19. Machine screw 19 passes also through a hole in member 9. The inner end of screw 19 is enlarged so that it may not be removed from the position shown in Figure 3; it is, however, free to rotate, the holes in members 9 and 1 serving as bearings. Screw 19 carries a threaded tab 6 perforated at its end to engage one end of spring 4, the other end of spring 4 being hooked around pin 5.

The numbers shown in Figures 2 to 7 inclusive represent members which are functionally identical with the numbers used in Figure 1.

In Figure 3, member B is shown rotated in a counterclockwise direction around pin 5 into engagement with the upper part of member R. The point of contact on R to member B in this position serves as the stop 3.

In Figure 3, it is also seen that the tongue 9a of member 9 extends between pin 5 and the bottom of member B. In this position, therefore, members R and B are rigid with respect to each other and pick-up arm 1 is free to rotate around fulcrum 11 in response to needle pressure on 12. The degree of this needle pressure, which is determined by the effectiveness of spring 4, is adjustable by a rotation of screw 19 which advances or retards tab 6 with which spring 4 is engaged.

If, however, no needle is present or if no record is present, the tongue of member 9 will strike pin 5 or the end of spring 4 which is wrapped around pin 5, one of these thereby performing the function of stop 7 of Figure 1, and will check the counterclockwise rotation of member 1 before damage is done to the record by an empty needle holder or to the turntable by the needle.

If it is now desired to put the pick-up arm out of the way and if pick-up arm 1 is for this purpose rotated in a clockwise direction, rotation will take place first of all around fulcrum 11 until the

position shown in Figure 6 is attained. At this instant, the tongue 9 will strike member B at the point 8, which serves as the stop shown in Figure 1. If the clockwise rotation of pick-up arm 1 is continued, assembly a and member B will become relatively rigid and rotate around pin 5. This rotation can be continued until pick-up arm 1 is in the vertical position shown in Figure 7. By this time, the center of gravity is obviously to the right of pin 5 and clockwise rotation would continue due to the weight alone, unless checked by a stop which would of course be provided in the most convenient manner.

It is possible to make the V notches 11 sufficiently deep so that the sides thereof, bearing against the sides of knife edge member 10, will furnish the stops 7 and 8.

To prevent the accidental removal of the knife edge 10 from V-groove 11, member B is drilled and threaded to receive screw 21, as shown in Figures 3 and 5. Member 9 is drilled with a large clearance hole 22 to pass screw 21. The clearance hole in member 9 is so large that it does not touch screw 21 under all normal conditions; however, it is now impossible to remove assembly A from member b without first removing screw 21 with a screw driver.

Figures 2 to 7 inclusive represent one practical embodiment of the mechanism of Figure 1 which accomplishes the purposes of the invention.

In the foregoing, I have described my invention only in connection with a specific effective embodiment thereof. Since my invention is capable of many variations and modifications which will be obvious to those skilled in the art, I prefer to be bound not by the specific disclosures herein but only by the appended claims.

I claim:

1. A phonograph tone arm mounting comprising a member rotatable in a horizontal plane, a tone arm support carried by said member; said support being rotatable with respect to said member in a vertical plane; a tone arm mounted on said support and rotatable with respect thereto in a vertical plane; means for limiting the rotation of said tone arm with respect to said support to a predetermined arc, said tone arm projecting substantially beyond its rotatable mounting on its support on one side of said mounting and projecting to a lesser degree on the other side of said mounting; and means for counterbalancing at least a portion of the weight of said tone arm on said first mentioned side, said last mentioned means comprising a spring connected at one end to said other side of the tone arm and at the other end to the pivot of said support.

2. A phonograph tone arm mounting comprising a member rotatable in a horizontal plane, a tone arm support carried by said member; said support being rotatable with respect to said member in a vertical plane; a tone arm mounted on said support and rotatable with respect thereto in a vertical plane; and means for limiting the rotation of said tone arm with respect to said support to a predetermined arc, said means comprising a dependent member connected to said tone arm; a pair of stop members on said support; said extension extending between said stop members.

3. A phonograph tone arm mounting comprising a member rotatable in a horizontal plane, a tone arm support carried by said member; said support being rotatable with respect to said member in a vertical plane; a tone arm mounted on said support and rotatable with respect thereto

in a vertical plane; and means for limiting the rotation of said tone arm with respect to said support to a predetermined arc, said means comprising a V-shaped notch at the upper end of said support; and a vertical knife edge extension of said tone arm engaging said notch, and an additional dependent member connected to said tone arm; a pair of stop members on said support; said extension extending between said stop members.
